UNITED STATES PATENT OFFICE

92,321

DESIGN FOR A COMBINATION LIQUID REGISTERING METER AND FAUCET

William H. Semon, Minneapolis, Minn., assignor
to National Liquid Register Company, Minne-
apolis, Minn., a corporation of Minnesota

Application February 26, 1934, Serial No. 50,868

Term of patent 3½ years

To all whom it may concern:

Be it known that I, WILLIAM H. SEMON, a citizen of the United States, residing at Minneapolis, in the county of Hennepin and State of Minnesota, have invented a new, original, and ornamental Design for a Combination Liquid Registering Meter and Faucet, of which the following is a specification, reference being had to the accompanying drawing, forming part thereof, wherein:—

Fig. 1 is a perspective view illustrating a com-

bination liquid registering meter and faucet embodying my new design;

Fig. 2 is a view in side elevation of the same; and

Fig. 3 is a view in front elevation of the same.

What I claim is:—

The ornamental design for a combination liquid registering meter and faucet, substantially as shown.

WILLIAM H. SEMON.
